SHOE AND PROCESS OF MAKING SAME

William H. Bain, Portsmouth, Ohio

Application April 5, 1933, Serial No. 664,559

3 Claims. (Cl. 12—142)

This invention relates to shoes of the kind having cushioned heel portions. It has for its principal objects to produce a shoe having a simple and efficient cushioned heel construction which will be strong and durable and of compact design, and to provide a simple and economical process of manufacturing such cushioned shoes. The invention consists in the cushioned shoe and in the process hereinafter described and claimed.

10 In the accompanying drawing, which forms part of this specification and wherein like symbols refer to like parts wherever they occur,

Fig. 1 is a perspective view of an insole forming part of a shoe embodying my invention,

15 Fig. 2 is a perspective view of the metallic heel piece employed in the process of manufacturing said shoe,

Fig. 3 is a perspective view of the pad for cushioning the heel of the shoe,

20 Fig. 4 is a vertical longitudinal section through the shoe during its process of manufacture, showing the position occupied by the metal heel piece during the operation of lasting the upper to the insole; and

25 Fig. 5 is a longitudinal sectional view of the finished shoe with the heel cushioning pad therein.

As shown in Fig. 5, my shoe comprises an insole A, an upper B attached thereto, an outsole C attached to the insole, and a cushioning pad D of rubber or other yielding material seated on the heel portion of the insole substantially flush with the inner face thereof. As shown in the drawing, the heel seat I is formed by reducing the thickness 30 of the heel portion of the insole an amount corresponding substantially to the thickness of the heel pad D. This reduced thickness is brought about preferably by removing the proper amount of material from the inner face of the heel portion of the insole A. The cushioning pad is cemented or otherwise held in its seat.

35 In the process of manufacturing the above cushioned shoe, the insole A is placed upon a last E with its heel seat I down. A metal plate F, having a shape and thickness corresponding to the shape and depth, respectively, of the seat in the heel portion of the insole is then interposed between the last and said seat and the upper is then lasted, in accordance with common practice, to the outer face of said insole, the lasting tacks 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960

The hereinbefore described cushioned heel construction is simple, economical and compact; it locates the cushioning pad flush with the upper surface of the insole in position to directly support the heel of the wearer; it permits removal and replacement of the pad without disturbing the other parts of the shoe and it provides a flush seat for said pad without changing the regular contour of the insole or outsole. The tacks, which secure the upper to the heel portion of the insole, are clinched thereon and thus cannot work loose; and the pad serves to prevent said tacks from coming in contact with the heel of the wearer. The process employed in making the shoe is simple and economical. The metal heel plate serves as a support for the thin heel portion of the insole while the upper is being lasted and the outsole is being laid, and it also serves as an anvil for clinching the lasting tacks which secure the upper to said portion of said insole.

Obviously, the hereinbefore described shoe and process of making same admit of considerable modification without departing from the invention. Therefore, I do not wish to be limited to the precise construction or process hereinbefore described.

What I claim is:

1. A shoe comprising a one-piece insole having a thin heel portion forming an open flat-bottomed seat that extends from side to side of said insole and to the heel end thereof, and a cushioning member mounted on said thin heel portion of said insole, with its inner face substantially flush with the inner face of the thick portion of said insole.

2. The process of making shoes having a cushioning pad in the heel portion thereof which consists in removing the inner surface of the heel portion of an insole to form an open seat that extends from side to side of said insole and to the heel end thereof, placing said insole on a last, interposing a metal member between said last and the seat in said heel portion of said insole, securing an upper to said seat of said last by tacks that are clinched by said metal member, removing said metal member from said seat and then inserting a cushioning member in said seat.

3. The process of making shoes having a cushioning pad in the heel portion thereof which consists in providing the inner face of the heel portion of an insole with a depressed seat that extends from side to side of said heel portion, placing said insole on a last, interposing a metal member between said last and the seat on said insole, lasting an upper to the heel portion of said insole, removing said metal member from said shoe and then inserting a cushioning member in said seat.
